Primary Examiner — Mark Goodwin*(74) Attorney, Agent, or Firm* — Husch Blackwell LLP**(57) CLAIM**

The ornamental design for a cup carrier with thumb holder, as shown and described.

DESCRIPTION

FIG. 1 is a perspective view of the cup carrier with thumb holder;

FIG. 2 is a top elevational view thereof; and,

FIG. 3 is a side elevational view thereof.

The features shown in broken lines depict environmental subject matter only and form no part of the claimed design.
